UNITED STATES PATENT OFFICE.

STEPHEN JARVIS ADAMS, OF PITTSBURG, PENNSYLVANIA, ASSIGNOR TO
MARCELLIN C. ADAMS, OF PITTSBURG, PENNSYLVANIA.

METHOD OF FORMING SAND MOLDS.

SPECIFICATION forming part of Letters Patent No. 697,388, dated April 8, 1902.

Original application filed March 30, 1897, Serial No. 629,919. Divided and this application filed February 6, 1901. Serial No. 48,162. (No model.)

To all whom it may concern:

Be it known that I, STEPHEN JARVIS ADAMS, a resident of Pittsburg, in the county of Allegheny and State of Pennsylvania, have invented a new and useful Improvement in Methods of Forming Sand Molds; and I do hereby declare the following to be a full, clear, and exact description thereof.

My invention relates to a method of forming sand molds, and more particularly to the method which is known as the "jarring" process, wherein the sand is placed around the patterns in the flask, a surplus of sand being held in a reservoir above the flask and the whole mass being raised and then permitted to drop or descend quickly and strike a stationary block, and thereby impart a jarring to the sand within the flask, a sufficient number of these jars being imparted thereto to compact the sand.

The present application is a division of my application filed March 30, 1897, Serial No. 629,919, and the invention herein claimed is designed to overcome certain difficulties existing in the methods of forming sand molds according to this system as heretofore practiced.

In the jarring process of forming sand molds as heretofore practiced the reservoir, which rested upon the top of the flask, consisted of a shallow frame open at both ends, which reservoir was filled with sand, which by the jarring operation passed down either entirely or mostly into the flask. I have discovered that the jarring stroke causes a rebound in this shallow body of sand within the reservoir and in the upper part of the flask and that while the sand is packed evenly and solidly around the lower portions of the pattern in the flask by reason of this rebound it is insufficiently packed in the upper part of the flask, so that the sand in the upper part of the flask is loose and spongy, thereby causing the formation of swells on the casting. In case the jarring operation is continued under this old process with the shallow body of sand above the flask in order to compact the sand more firmly in the upper portion of the flask the said upper portion becomes cracked and filled with crevices, thereby rendering it wholly impractical.

It has therefore been found necessary in such jarring process to compact the sand in the upper portion of the flask by means of a hand-tool after the jarring operation is completed. This, however, is open to the defect that it forms a crust or solid layer of sand in the upper portion of the flask, which prevents the escape of gases and steam, which are always present in the casting operation, due probably to the organic matter existing in the sand or to other causes. As a consequence it has been found necessary to puncture or perforate the mold by means of a prod or wire in order to permit the escape of gases and steam.

The object of the present invention is to overcome these defects in the old method of forming sand molds according to this system and to provide a method of forming such molds which insures the even packing of the sand in the mold throughout its height, thereby forming a mold which is more perfect than under the old process, which will not result in the formation of swells in the casting, and in which the sand is homogeneous throughout, so that the sand in the upper portion thereof while it is compacted is still porous enough to permit an escape of steam and gases from the mold. This object I accomplish by the employment of a superincumbent column of sand above the flask of sufficient height to provide a body of sand having sufficient weight to prevent the rebound of the sand within the flask, so that the sand in the upper portion of the flask will be packed as firmly as the sand in the lower portion of the flask, thereby forming a mold which will not produce swells on the casting and which has the sand in the upper portion thereof firm, but porous, so that the gases or steam can readily escape.

To enable others skilled in the art to practice my invention, I will describe a suitable form of apparatus for carrying the same in effect, such apparatus being illustrated in the accompanying drawings, in which—

Figure 1 is a side elevation of such apparatus partially broken away. Fig. 2 is a cross-section of the same on the line 22, Fig. 1; and Fig. 3 is a perspective view of the flask and the base of the sand-feeding chute, illustrat-

ing the cutting and sleeking of the mold, said view being partially broken away.

- The apparatus illustrated comprises the framework A, which rises from the bed or floor 5 b', which also supports the jarring-block b, said framework being composed of upright standards a and any suitable cross-beams a'. The apparatus has also the jarring-table c and the sand-feeding chute d, which is, at 10 least during the jarring operation, supported on said table independently of the flask, being preferably permanently supported on the table. The upright standards a carry suitable guides or guideways, which, as shown, 15 are placed a sufficient distance apart to insure the absolutely-vertical movement of the jarring-table and sand-feeding chute. As illustrated, there are the lower guideways e, which are engaged by guides e' on the jarring-table 20 c, and the upper guideways f, engaged by guides f' near the upper end of the chute d. As it is desirable to protect the guides and guideways from contact with the sand, which is liable to cut and wear into the same, I prefer to extend the guides e' upwardly from the 25 jarring-table c to a point above the base of the chute d, so that there will be no liability of the sand entering between the guides and guideways. The sand-feeding chute is supported some distance above the jarring-table 30 on suitable legs d' d'', the legs d' being placed two on each side near to the front and back faces of the chute, while the legs d'' are placed about midway and provide bearings for the 35 cams g, which act to clamp upon the jarring-table the flask h, in which the mold is made, the flask h having lugs h' in line with said cams g, so that after the flask is inserted under the sand-feeding chute the cams may be 40 thrown down by means of the handles g' and force the flask against the jarring-table and hold it firmly during the jarring operation. Suitable rests or supports for the handles g' when the cams are not in use may be provided 45 upon the legs d''. It will be noticed that between the flask h and chute d a slight space is left, as at h'', this space being provided for the passage of the cutting and sleeking mechanism referred to hereinafter.
- The sand-feeding chute is made with a 50 slight upward taper, increasing gradually in diameter from the top to the bottom, so as to prevent the sand from sticking therein. It is preferable to make this chute from eight to ten feet in height, so that it will hold a 55 large body of sand and so that the sand in the lower part thereof will be sufficiently packed in any ordinary diameter of chute to maintain the weight of the sand above without dropping out. Its principal function is to resist any tendency to rebound of the sand 60 within the flask, providing in this way a body of sand which can only be caused to move by the jars imparted to the chute and which 65 will remain therein when the flask is withdrawn from under the chute and before it is again placed thereunder for the making of

the next mold. If any difficulty is experienced in the holding of the sand in the chute, it can be overcome by the employment of a few wires d', extending across the base thereof; but this is only necessary in forming molds of considerable width. The supply of sand may be maintained within the sand-feeding chute in any suitable way, being fed thereto by proper mechanism.

In order to raise and lower the jarring-table and its sand-feeding chute, I may employ any suitable vertically-moving mechanism operating in any suitable way, the preferable way being by steam or air pressure operating within an engine K, having a cylinder k, which operates through the piston k' a piston-rod k'', from which the sand-feeding chute d is suspended by a flexible support l, which is preferably formed of a wire rope, the advantage of this construction being that the power to lift the table and chute being applied through a flexible connection permits the same to move as guided from the frame, and therefore permits it to move in an exactly vertical course in dropping, the lifting mechanism having no control whatever upon the dropping of the table and its chute. In order to give a direct upward pull of the wire 90 rope l to the chute, it is passed first around a pulley k''' on the lower end of the piston-rod k'' and thence passes around the pulleys l', supported on the cross-beam a', and in such position that the rope then passes in a true vertical course down to the loops l'', by which it is connected on each side to the sand-feeding chute d. The admission and escape of air or steam to the cylinder k of the lifting-engine is controlled by any suitable valve 95 mechanism operating through the valve-chest m, the valve-rod m being under any suitable control. The construction of the engine will of course require a rapid escape of the air to permit the jarring stroke; but this can be obtained by the use of a cylinder somewhat longer than the stroke, which will at the same time permit the piston to cushion before reaching the lower end of the cylinder, while the stroke of the piston and its rod may 100 be controlled by a suitable stop n, the piston-rod extending up through the upper cross-beam a'', to which the cylinder k is connected, and having a head or enlargement n', which engages with said stop n, a suitable spring 105 or other cushion n'' being interposed between the same, as found necessary. The stroke of the apparatus—that is, the lift of the table and its chute above the jarring-block b—of course depends upon the mold being made 110 and the particular stroke necessary for the packing of the sand. On an average a lift of about one foot will be sufficient, and the cylinder and valve mechanism can of course be made of proper construction to give such 115 stroke, permitting a free drop and the cushioning of the piston.

It will of course be understood that the sand is packed solidly in the lower part of the feed-

ing-chute and the upper part of the flask and that before the finished mold can be withdrawn this sand must be properly cut, so as to permit the withdrawal of the flask. As above stated, a space h^2 is left between the top of the flask h and the bottom of the sand-feeding chute d , the space varying in different mechanisms, but being generally about one-half an inch in width. To cut off the sand, I employ a cutting and sleeking frame p , which, as shown in the drawings, is formed of a light frame, having two arms p' extending forward and carrying at the front end a wire p^2 , stretched taut between said arms, the arms being of a thickness such as to pass easily through the space h^2 between the flask and chute, so that when this frame is pushed horizontally through said space the thin wire cutter will cut through the sand, and so form a division thereof, separating the sand within the flask from that within the chute. As the wire cutter forms a rough surface upon the sand, in order to sleek the sand within the flask and also to aid in packing the sand at the base of the feeding-chute I employ back of the sand-cutter the sand-sleeker p^3 , which, as shown, is formed of a slat corresponding in thickness to the frame p and tapering gradually to an edge on one or both sides, as at p^4 , so that as the wire cuts through the sand this sleeker will follow it and smooth over the surface of the sand both above and below it, preferably having this action both in the entering and withdrawing stroke of the frame, and so smoothing the surface of the finished mold and packing the sand up into the chute d , which will increase the binding force of the sand at the base thereof and so aid the same in holding the sand above it within the chute.

When the apparatus above described is employed in the making of molds, I generally proceed as follows: The sand for filling the flask may either all be drawn from the sand-feeding chute or a certain portion of mealy sand—such as will conform more perfectly to the pattern r , which extends up from the pattern-plate r' into the flask h —may first be filled around said patterns before the pattern-plate and flask are placed in position under the sand-feeding chute, such feeding of mealy sand being accomplished by hand or in any suitable way. The pattern-plate, with the flask resting thereon, is placed on the jarring-table c under the sand-feeding chute and is clamped in place by the cams g . The apparatus is then ready for the making of the mold, and through the movement of the valve mechanism controlling the lifting-engine K the jarring-table and its sand-feeding chute are raised and dropped, so that the jarring-table c strikes the jarring-block b and imparts the jar to the same, the action of which is to jar the sand from the sand-feeding chute down into the flask, either filling the flask entirely through said chute when the empty flask, with its patterns, is placed under the same or filling the portion of the flask unfilled with sand. In so doing the sand from the chute acts as a weight upon the sand in the flask and prevents the rebound of the sand from the jar in the upper part of the flask, which has been the serious defect in the prior methods employed in this system of molding, so that the entire effect of the jar in packing the sand within the flask is obtained, the whole body of sand within the long feeding-chute moving down at each jar and holding the sand to the position to which it is brought by the jar without permitting any rebound thereof, the only rebound being in the sand in the upper part of the sand-feeding chute, where it can have no effect whatever upon the sand packed within the flask. Any suitable number of jars may thus be imparted to the sand within the flask and chute to give the necessary degree of solidity within the flask, as can be easily determined according to the length of the stroke and the depth of the mold to be formed. When the mold is completed, the operator grasps the cutting and sleeking frame p and pushes it through the space h^2 between the flask and chute and the wire p^2 cuts through the sand, while the sleeker p^3 , following the wire, smooths the surface of the sand both of the mold and at the bottom of the chute, so finishing the top surface of the mold and aiding in packing of the sand at the base of the chute, which will increase the hold thereof and assist it in holding the mass of sand above it. The clamping-cams g are then withdrawn and the flask drawn out horizontally and the patterns withdrawn and any necessary cores inserted in the mold, thus completing it. A new flask may then be placed upon the pattern-plate and the operation repeated. The sand within the feeding-chute can be maintained at the proper height by means of any suitable feeding mechanism.

It will be seen that by the method described the entire body of sand within the flask is packed to a uniform density, so that every portion of the mold-walls offer an equal resistance to the molten metal in the mold, and said mold is of equal porosity at all points, so that gas and steam can readily escape therefrom.

What I claim as my invention, and desire to secure by Letters Patent, is—

The herein-described method of forming sand molds, consisting in imparting a jar to a flask containing sand around the pattern and to a superincumbent body of sand of sufficient height to act as a weight and prevent rebound of the sand in the upper part of the flask in the jarring action.

In testimony whereof I, the said STEPHEN J. ADAMS, have hereunto set my hand.

STEPHEN JARVIS ADAMS.
